UNITED STATES PATENT OFFICE.

FERGUS F. WILSON, OF BROOKLYN, NEW YORK, ASSIGNOR TO ALBERT J. KELTING, OF BROOKLYN, NEW YORK.

BLOWER.

SPECIFICATION forming part of Letters Patent No. 738,868, dated September 15, 1903.

Application filed March 6, 1903. Serial No. 146,531. (No model.)

To all whom it may concern:

Be it known that I, FERGUS F. WILSON, of the borough of Brooklyn, county of Kings, city and State of New York, have invented certain 5 new and useful Improvements in Blowers, of which the following is a specification, accompanied by drawings.

This invention relates to blowers, but more particularly to that class known as "positive-pressure" blowers, in which there is a rotating piston and rotary wings or blades actuated thereby and constructed to oscillate at the same time in the direction of the axis of rotation.

15 The objects of the invention are to improve upon the construction of such blowers and increase their efficiency, while rendering the parts less liable to get out of order than heretofore.

20 Another object of the invention is to improve upon the bearings of the rotating and oscillating wings or blades, whereby wear may be readily taken up and provision afforded for adjusting the parts automatically.

25 Further objects of the invention will hereinafter appear, and to these ends the invention consists of apparatus and devices for carrying out the above objects, embodying the features of construction, combinations of elements, and arrangement of parts, having the general mode of operation substantially as hereinafter fully described and claimed in this specification and shown in the accompanying drawings, in which—

35 Figure 1 is a central sectional elevation taken in the plane of the shaft of apparatus embodying the invention. Fig. 2 is a horizontal sectional view of the apparatus in the plane of the shaft. Fig. 3 is a central sectional elevation of the blower transversely of the shaft. Fig. 4 is a perspective view of one of the bearing-blocks for the blades. Fig. 5 is a detail side view of a portion of the apparatus, showing one of the blades in operative 40 position in its bearing-block. Fig. 6 is a detail view showing the rear of one of the blades and its bearing.

45 Referring to the drawings, the wedge-shaped frame or rim A is provided with the

covers B, suitably secured thereto, as by 50 means of the bolts C, while legs D are formed upon the frame. Within the framework thus formed a piston E is adapted to be rotated, and in the class of blowers referred to the piston is formed with conical surfaces F. 55

The blower may be constructed either single or double, in this instance a double blower being shown, and the piston E comprises two halves or sections suitably secured together, as by means of the screws G, but one of which 60 screws is shown in dotted lines in Fig. 1 to illustrate the construction. The double conical piston E is provided with slots in its sides at substantially right angles to each other, in which the wings or blades H are adapted to oscillate as they rotate with the rotating piston. 65

The covers B are bored, as shown, at an angle to afford bearings for the horizontally-extending hubs I of the piston, which hubs, as shown, are inwardly screw-threaded to receive the screw-threaded ends of the shaft J. Any suitable means may be provided for imparting rotation to the shaft J to operate the apparatus. If desired, pins K may be utilized to secure the shafts firmly within the 70 hubs I. Bearing-boxes L are suitably secured to the covers B, as by means of the screws O, and adjusting-screws P afford provision for compensating for wear in the boxes. 75

According to the construction of frame and piston described it will be seen that compression-ways Q are afforded at each side of the piston in the lower portion of the apparatus, while communication between the said compression-ways is cut off at the abutment 80 R, which is afforded between the upper portions of the piston and covers. In the operation of the apparatus the wings swing outwardly into the compression-ways during rotation and retire within the slots in the piston at the upper portion of the apparatus. The frame A is provided with a cylindrical portion S for the periphery of the piston, while the outer curved edges of the wings are adapted to the curved portions T of the frame A. 85 There is a clearance-space U at each side of the apparatus, with which inlet and outlet passages V V' and W W' communicate. An 90 95

abutment X, as shown, separates the clearance-spaces U. It will be seen that air entering the compression-ways one side or the other, according to the direction of rotation 5 of the piston, will be forced out the other side by the wings, which oscillate on their pivots, as stated, to swing out into the compression-ways at one side of the axis of the piston, to take effect on the air and retire at the 10 other side of said axis in order to sweep past the abutments afforded by the covers of the casing.

According to the invention improved bearings are afforded for the blades or wings of 15 the blower. As shown, the hubs I of the piston are hollow, and inwardly-extending webs Y afford cylindrical supports for the bearing-blocks Z of the blades. According to the invention the blades H are permitted to oscillate freely upon their trunnions 1, which are afforded bearings in the recessed or U-shaped portions 2 of the bearing-blocks. The bearing-blocks are also slotted at 3, at right angles to the slots or forks 2, to afford provision 20 for the oscillation or vibration of the blade in the bearing-block.

In assembling the parts of the apparatus the trunnions 1 of a blade are first placed within the bearing-slots 2 and then the bearing-block is thrust within the cylindrical socket afforded by the web Y of one-half of the piston, as shown. In order to prevent wear of the edges 4 of the blades against the inside of the covers, revoluble rings 5 are secured 35 within the circular grooves 6 in the inside faces of the covers, while projections 7 on the blades fit notches 8 in these rings 5. The inside edges 4 of the blades may be covered with felt or other suitable substance to 40 bear upon the inside faces of the covers. Wear between the blades and the covers is taken up by the pressure of the spring 10, which, as shown, is arranged between the ends 45 of the bearing-blocks and tends to force each bearing-block outwardly.

According to this improved construction strong and efficient bearings are afforded for the rotating or oscillating or vibrating blades. Wear is automatically taken up and the parts 50 are not liable to get out of order or become broken. Proper adjustment of the parts is always maintained, for as wear occurs the bearing-blocks Z are pushed farther within the sockets or supports Y to compensate therefor. The apparatus may be operated at high 55 speeds without derangement of the parts, and all of the parts of the construction are interchangeable.

According to the invention it will be seen 60 that the wings are adapted to be oscillated about axes transverse to the axis of rotation, and the bearing-blocks are carried by the piston and are movable in the direction of the axis of the piston. The wings are pivotally 65 supported upon the bearing-blocks, and elas-

tic means are provided for pressing said blocks into their seats. - Each bearing-block is provided with a slot, which is adapted to register with the slots in the piston, and the bearing-recesses in the bearing-blocks for the trunnions of the wings are arranged, as shown, transversely to the slots in the blocks. The wings, it will be seen, are adapted to oscillate in the slots in the piston and in the bearing-blocks.

My improved construction affords an equal distribution of the strain or pressure upon all of the bearings, giving to each bearing an equal amount of wearing and also an equal amount of duty. Clogging or breakage of 80 any of the moving parts is also prevented should any foreign material enter the mechanism.

Obviously some features of this invention may be used without others, and the invention may be embodied in widely-varying forms.

Therefore without limiting the invention to the construction shown and described nor enumerating equivalents, I claim, and desire 90 to obtain by Letters Patent, the following:

1. In a pressure-blower, the combination with the casing and rotary conical piston, of wings rotating with the piston and adapted to be oscillated about an axis transverse to 95 the axis of rotation, bearing-blocks carried by the piston and movable longitudinally of the axis of rotation, said wings being pivotally supported upon the bearing-blocks, and a spring compressed between the inner ends 100 of said blocks and tending to force them outwardly, for substantially the purposes set forth.

2. In a pressure-blower, the combination with the casing and rotary conical piston provided with a slot, of a bearing-block carried by the piston and provided with a slot adapted to register with the slot in the piston, said block also being recessed at one end transversely to the slot therein, wings provided 110 with trunnions pivotally supported in the transverse recesses in the end of the block, the wings being adapted to oscillate in the slots in the piston and bearing-block, and elastic means for pressing said bearing-block 115 into its seat to take up wear, for substantially the purposes set forth.

3. In a pressure-blower, the combination with the casing and rotary conical piston provided with a slot, of a solid bearing-block 120 carried by the piston and provided with a slot adapted to register with the slot in the piston, the tongues formed by the slot in said block being recessed at their outer ends transversely to the said slot, wings provided with 125 trunnions connected thereto and pivotally supported in the transverse recesses in the ends of said tongues, the wings being adapted to oscillate in the slots in the piston and bearing-block, and elastic means arranged to 130

exert direct pressure upon the rear portion of
said bearing-block for forcing the block into
its seat to take up wear, thereby affording
substantially equal distribution of strain or
5 pressure upon the trunnions of the wings, for
substantially the purposes set forth.

In testimony whereof I have signed my

name to this specification in the presence of
two subscribing witnesses.

FERGUS F. WILSON.
